DEEP WELL DRILLING APPARATUS

William P. Rogers, Pampa, Tex.

Application August 13, 1938, Serial No. 224,780

3 Claims. (Cl. 255—11)

This invention relates to a deep well drilling apparatus, and it is primarily an object of the invention to provide an apparatus of this kind which is portable whereby it can be transported 5 from one operation to another.

It is also an object of the invention to provide an apparatus of this kind which comprises three major units, namely, a power unit, a mast unit, and a bull wheel unit, the same being initially 10 entirely separate one from the other so that the various units if desired can be independently used or assembled in a manner to provide a complete drilling assembly.

Another object of the invention is to provide an 15 apparatus of this kind constructed and assembled in a way whereby the power unit and the mast unit are at opposite sides of the well and assembled in a manner to provide a considerable area immediately adjacent to the well and between 20 said units to allow for freedom of movement for the workmen.

A further object of the invention is to provide an apparatus of this kind comprising several 25 separate units, namely, a power unit, a mast unit, and a bull wheel unit and wherein said units are relatively mounted in a complete assembly to allow such coaction between the units to maintain the same in balance or against upending or 30 tilting.

30 The invention consists in the details of construction and in the combination and arrangement of the several parts of my improved deep well drilling apparatus whereby certain important advantages are attained and the device rendered 35 simpler, less expensive and otherwise more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein—

45 Figure 1 is a view in side elevation illustrating a deep well drilling apparatus comprising an assembly of separate units constructed and arranged in accordance with an embodiment of my invention;

50 Figure 2 is a view in top plan of the assembly as illustrated in Figure 1;

Figure 3 is a sectional view taken substantially on the line 3—3 of Figure 2 looking in the direction of the arrow.

55 Figure 4 is a detailed vertical sectional view

taken substantially on the line 4—4 of Figure 3 looking in the direction of the arrow;

Figure 5 is a fragmentary view partly in horizontal section and partly in top plan showing the detachable connection between the mast unit and 5 the power unit as herein disclosed;

Figure 6 is a view in top plan of the crown block of the mast and an additional sheave being indicated by broken lines;

Figure 7 is a detailed sectional view taken substantially on the line 7—7 of Figure 6;

Figure 8 is a detailed sectional view taken substantially on the line 8—8 of Figure 5;

Figure 9 is a detailed sectional view taken substantially on the line 9—9 of Figure 4; 15

Figure 10 is a sectional view taken substantially on the line 10—10 of Figure 9;

Figure 11 is a view somewhat similar to Figure 9 but showing the mast in a lowered position;

Figure 12 is a fragmentary view partly in section and partly in elevation illustrating an embodiment of the invention wherein the drilling line has interposed therein a traveller block for increasing the pull of the drilling line. 20

As disclosed in the accompanying drawings, my 25 improved apparatus comprises three separate units, namely, a power unit P, a mast unit M and a bull wheel unit B. These various units are to be readily assembled when it is desired to provide 30 a complete drilling apparatus or when preferred they may be separately used.

The power unit P as herein disclosed comprises a base frame consisting of the conventional side sills 1 which are preferably of an H type together with the rear cross beam 2 also of an H type 35 and with other suitably positioned cross beams 3 as the assembly of the power unit may necessitate. This power unit P is of a type now generally in use which includes the walking beam 4 mounted in a conventional manner upon the upstanding Samson post 5. This Samson post 5 is supported in a conventional manner at the rear left corner portion of the base frame of the power unit P. Associated with this Samson post 5 is a forwardly directed brace 6 which extends from 40 the upper portion of the Samson post 5 to a point on an adjacent side sill 1 in advance of the post. Other braces may be employed in connection with this Samson post as deemed advisable and necessary. The Samson post 5 also has 45 secured to its upper portion a second brace post 6a which is disposed on a forward and downward incline with its lower or free end portion terminating at a predetermined point spaced outwardly from the rear cross member 2. 50

55

The power unit P comprises an engine E of any preferred type which is in driven connection in a well known manner with a band wheel assembly 7. This band wheel assembly 7 is in driving connection in a well known manner with the sand reel 8 for a bailing line 9. As this power unit P is substantially the same as the power units now generally in use in connection with deep well drilling it is not believed necessary that the same be described in any further detail.

The mast unit M comprises two parallel and suitably spaced side sills or beams 10 also preferably of an H type and the forward extremities of these sills or beams 10 are connected by a channel beam 11. As is particularly illustrated in Figures 5 and 8 this channel beam 11 is secured to the adjacent or forward end portion of the sills or beams 10 of the mast unit M by the brackets 12.

When the mast unit M is in assembly with the power unit P said mast unit M is laterally offset with respect to the unit B as illustrated in Figure 5 so that the walking beam 4 will be in proper position with respect to the well and also with respect to the sheave at the top or crown of the mast over which the drilling line passes. In this assembly of the power unit P and the mast unit M the forward cross beam 11 butts or contacts, as is clearly illustrated in Figures 5 and 8, with the rear edges of the flanges of the rear beam 2 of the frame of the power unit and the bolts 14 for connecting the beam 11 to a bracket 12 also pass through and coat with the web portion of the beam 2 to provide a detachable connection between the beams 2 and 11.

The rear cross beam 2 of the base frame of the power unit P is also secured to brackets 15 suitably secured to the inner faces of the webs of the sills or beams 1. The bolts 16 for holding the beam 2 to the sill 1 at the left side of the base frame of the power unit are also directed through the beam 11 to provide a further means for detachably connecting and holding the beam 11 to the beam 2. It is believed to be obvious that when it is desired to separate the units P and M it is only necessary that the bolts 14 and 16 be removed.

At a desired point inwardly of their forward ends the side sills or beams 10 of the mast unit M are connected by a cross beam 17 and when the units P and M are in assembled relation the brace member 6^a hereinbefore referred to contacts from above with this cross beam 17 as particularly illustrated in Figure 3. The lower end portion of the brace 6^a is provided with a foot 18 whereby it may be detachably connected, as at 19, by a bolt or otherwise as may be desired with the upper flange of the beam 17 which, as disclosed in the accompanying drawings, is of an H type. It will, therefore, be noted that in the assembly of the units P and M the brace member 6^a in its connection with the unit M provides further reinforcement for the Samson post 5 but this arrangement and connection of the brace member 6^a is of further importance and advantage in the fact that by its connection with the unit M upending of the forward end of the power unit is prevented while, of course, upending of the rear end of the mast unit is avoided.

The rear portions of the beams or sills 10 of the mast unit are provided with the transversely spaced shoes 20 with which are pivotally connected, as at 21, the lower end portions of the legs 22 of the mast. These legs 22 are comprised in a conventional fabrication of a mast except

that the crown block 23 at the top of the mast comprises two parallel shafts 24 and 25 herein disclosed as non-rotatable.

Freely mounted for rotation on the shaft 25 is the sheave 26 for the bail line 9. The shaft 24 has freely mounted for rotation thereon a crown sheave 27 over which passes in a conventional manner the drill line 28. This drill line 28, as is well known, is operated by the beam 4 and leads from the tug wheel 29 of the bull wheel structure to be hereinafter referred to.

As particularly illustrated in Figures 9 and 11, the lower rear corner of each of the legs 22 is rounded, as at 30, so that the mast when desired may be readily swung downwardly and rearwardly and particularly to facilitate transportation.

When the mast is raised for use in drilling it is, of course, imperative that the crown sheave 27 be positioned substantially directly above the well 31 so that the depending portion of the line 28 carrying the tools will be substantially vertical.

To assure the proper positioning of this crown sheave 27, the lower end of each of the legs 22 is disposed on an upward and forward incline, as at 32, and on such degree with respect to the longitudinal axis of the legs 22 so that when the bottom edges or ends 32 contact with the base plates 33 of the shoes 20 the mast will be disposed on the required forward incline.

The crown sheave 27 is held in desired position upon its shaft 25 by the thrust sleeves 34 held to the shaft 25 by the set screws 35 or the like.

When the load of the tools carried by the line 28 is unusually heavy or said tools become stuck within the well requiring greater pull on the part of the line, a second sheave 36 is mounted for rotation upon the shaft 25 and, as is illustrated in Figure 12, the drill line 37 leading from the bull wheel extends over the sheave 27 and then down for operative engagement with a traveller block 38 and then up and over the second sheave 36 and then down to and anchored, as at 39, to the traveller block. The traveler block in this assembly has suitably secured thereto, as at 40, a supplemental tool line 41 which directly carries the tools.

The bull wheel unit B comprises the spaced parallel base beams 42 of desired length and which, as herein disclosed, are of an H type. These beams 42 at their extremities have the bottom flanges thereof formed to provide the upwardly curved shoes 43 which facilitate the transporting of the unit B when the same is drawn over a surface with the beams 42 serving as runners. These beams 42 are maintained in desired spaced relation by the suitably positioned cross members 44 and mounted directly upon these beams 42 is a conventional bull wheel structure 45 from which the line or cable 28 leads as is well known. As the detailed assembly of the bull wheel structure forms no particular part of the present invention and is of a type now generally in use, it is not believed that a detailed description thereof is necessary.

This bull wheel unit B is capable of independent use when so desired but when in assembly with units P and M to provide a complete well drilling apparatus, this unit B is mounted upon the sills or beams 10 of the unit M rearwardly of the mast with the beams 42 of the unit B extending transversely across the beams or sills 10. When so positioned bolts 46 or the like are disposed through the lower flanges of the beams 42 and the upper flanges of the beams or sills 10 detach-

ably hold the unit B upon the sills or beams 10 of the mast unit M.

The bull wheel unit B includes the conventional upstanding frame structure 47 and detachably connected to the upper portion of this frame structure 47 for coaction with each of the legs 22 of the mast when raised is a brace member 48. This detachable connection of the frame structure 47 is preferably through the medium of the 10 removable bolts 49. The upper end portion of this brace member 48 is detachably connected by the bolts 50 with the associated leg 22 of the mast as is particularly illustrated in Figure 3. When the mast is raised there is also secured to 15 each of the legs 22 thereof and in advance of the mast a supporting or bracing member 51. Each of these brace members 51 is detachably bolted or otherwise connected, as at 52, with a leg 22 at a desired point above the pivotal mounting of 20 said leg 22 while the lower extremity of each of these members 51 is detachably connected by the bolts 53 or the like with a sill or beam 10 of the mast unit M. Each of the brace members 51 at a predetermined point intermediate its ends is 25 provided with the inwardly directed brace struts 54 which are detachably connected by the bolts 55 with the adjacent portion of the associated leg 22 of the mast.

The bull wheel structure 45 as herein disclosed 30 comprises, as is believed to be apparent from the drawings, the tug wheel 29 at one end thereof and the brake wheel 56 at the opposite end thereof. As illustrated in Figure 4, it is to be noted that the tug wheel 29 and the brake wheel 56 35 of the bull wheel structure 45 are spaced apart a distance so as to have the tug wheel 29 positioned entirely to one side of the mast and the brake wheel 56 positioned entirely beyond the opposite side of the mast. This is of advantage 40 as the tug wheel when so positioned permits the ready removal or application of the rope or line with respect thereto while the brake wheel 56 is free to assure effective braking action.

The Samson post 5 and the braces associated 45 therewith support in a well known manner, as at 57, the upper portion of a conventional headache post 58. When the units B and M are assembled 50 this headache post 58 contacts from above with the cross member or beam 17 and is detachably secured thereto, as at 59, by bolts or the like.

When the unit M and unit P are in assembly, 55 it is also of advantage to provide the brace member 60 detachably connected, as at 61, by bolts or the like to the rear portion of a side sill 1 and 55 also detachably connected, as at 62, by bolts or the like to the adjacent outer end portion of the beam 11.

From the foregoing description it is thought 60 to be obvious that a deep well drilling apparatus constructed in accordance with my invention is particularly well adapted for use by reason of the convenience and facility with which it may be assembled and operated, and it will also be 65 obvious that my invention is susceptible of some change and modification without departing from the principles and spirit thereof and for this reason I do not wish to be understood as limiting myself to the precise arrangement and formation of the several parts herein shown in carry-

ing out my invention in practice except as hereinafter claimed.

I claim:

1. A well drilling apparatus comprising, in combination, a power unit including side sills and a cross member connecting the rear extremities of said side sills; a mast unit including side sills and a cross member connecting the forward extremities of said side sills; means coacting with the cross members of both of the units for detachably connecting said units one to the other, a Samson post carried by the rear portion of the power unit, a brace member extending from the upper portion of the Samson post and extending beyond the adjacent rear end of the power unit to contact with the mast unit from above, means for detachably connecting said brace member to the mast unit, said brace member providing means to prevent upending of the forward end portion of the power unit and of the rear end portion of the mast unit.

2. A well drilling apparatus comprising, in combination, a power unit including side sills and a cross member connecting the rear extremities of said side sills; a mast unit including side sills and a cross member connecting the forward extremities of said side sills; means coacting with the cross members of both of the units for detachably connecting said units one to the other, a Samson post carried by the rear portion of the power unit, a brace member extending from the upper portion of the Samson post and extending beyond the adjacent rear end of the power unit to contact with the mast unit from above, means for detachably connecting said brace member to the mast unit, said brace member providing means to prevent upending of the forward end portion of the power unit and of the rear end portion of the mast unit, a headache post operatively supported by the Samson post and the brace member, said headache post being positioned beyond the rear end of the power unit, and means for detachably connecting the headache post to the forward portion of the mast unit to provide further means to prevent upending of the forward end of the power unit and the rear end of the mast unit.

3. A well drilling apparatus comprising, in combination, a power unit including a base structure having a rear cross member; a mast unit including a base structure having a forward cross member; means for detachably connecting the cross members of the units with the mast unit laterally offset with respect to the power unit, a Samson post carried by the rear portion of the base structure of the power unit at the side thereof beyond which the mast unit is offset, a walking beam mounted upon the Samson post, the mast unit being offset with respect to the power unit a distance to position the walking beam at substantially the transverse center of the mast unit, a mast carried by the base structure of the mast unit at a point materially inward from the forward end of said mast unit, and means carried by the Samson post for coaction from above with the mast unit to prevent upending of the forward end portion of the power unit and of the rear end portion of the mast unit.

WILLIAM P. ROGERS.
